UNITED STATES PATENT OFFICE.

CHARLES W. BELL, OF BARTLESVILLE, OKLAHOMA.

PUMP FOR OIL AND LIKE WELLS.

1,114,721.

Specification of Letters Patent.

Patented Oct. 27, 1914.

Application filed November 15, 1913. Serial No. 801,301.

To all whom it may concern:

Be it known that I, CHARLES W. BELL, a citizen of the United States, and resident of Bartlesville, in the county of Washington and State of Oklahoma, have invented a new and useful Improvement in Pumps for Oil and like Wells; and I do hereby declare the following to be a full, clear, and exact description thereof.

10 My invention relates to pumps for oil and like wells.

In a patent granted to me May 9th, 1911, 991,600, there is set forth and claimed a method of reducing the wear of valves and 15 plungers in oil-well pumps, said method consisting in separating the gas from the oil and admitting the gas thus separated from the oil to and around said valves and plungers, thereby sealing the same against 20 the entrance of liquid. By this method the fine sand which is present in the oil, due to the shooting of the well, is prevented from settling on the valves and plungers, and causing the rapid wearing away of the cups 25 and packing.

The object of the present invention is to provide a simple form of apparatus for carrying out the above method, and to these ends my invention comprises the novel features hereinafter set forth and claimed.

In the accompanying drawing, Figure 1 is a vertical section of my improved pump, with the piston ascending; Fig. 2 is a like view, showing the piston descending, and 35 Figs. 3 and 4 are enlarged sections; Fig. 5 is a cross section on line 5—5, Fig. 4.

Referring to the drawing, the numeral 2 designates the working-barrel which is threaded into the collar 3 at its lower end. 40 Threaded into the collar 3 is the perforated pipe 4, through which the fluid passes from the well into the pump. In the collar 3 is formed the tapered shoulder 5, which forms the support for the ordinary standing-valve 6. This valve is provided with the cage 7 and the ball-valve 8. The upper end of the working-barrel 2 is threaded into the enlarged extension 9. The upper end of the extension 9 is connected to the tubular section 10. The upper end of the tubular section 10 is connected to the collar 11, which connects said tubular section 10 with the tubing 12, leading to the top of the well.

Within the working-barrel 2 is the ordinary cup-piston or plunger 13. The upper

end of the plunger 13 is threaded into the valve-member 14. This valve-member 14 forms the housing for the ball-valve 15, and has the shoulder 16, which forms a rest for the valve-seat 17, and by means of which 60 said valve-seat is held in place on top of the plunger 13.

The valve-member 14 is provided with the apertures 18, which form a passage-way for the fluid to pass from the housing into the tube 19, which is threaded to the upper end of the valve-member 14. The tube 19 being connected to the valve-member and the valve-member in turn to the plunger, the tube 19 thus becomes a part of said plunger 70 and moves up and down therewith.

A piston-rod 20 is connected to the valve-member 14 at its lower end and at its upper end is connected to the pump-rod 21 leading to the top of the well.

Within the tubular extension 10 is the self-sustaining member 22, and said member is held within said tubular extension by means of the expandable ring 23 which is held between the collar 24 and the shoulder 80 25. The packing-cup 26 rests on the upper end of the collar 27, which is threaded to the member 22, and said packing-ring is forced out against the inner walls of the tubular section 10 by the expanding ring 85 28. This expanding ring 28 is preferably a split steel ring with sufficient expansion action to force the packing 26 tightly against the inner wall of the tubular section 10, so as to prevent the fluid from getting in from 90 above, or the gas from getting in from below.

A tube 29 is connected to the lower end of the collar 27 and said tube extends down within the tube 19 to a point adjacent to the 95 valve-member 14.

In the operation of my improved pump, when the plunger is raised, as shown in Fig. 2, the fluid enters the well and passes up through the valve 8 into the lower end of 100 the working-barrel while the valve 15 is closed. Upon the descent of the plunger, the valve 8 is closed, and the fluid passing up through the plunger lifts the valve 15 which permits the fluid to pass on up above 105 the plunger and into the pipe 19. At the same time that the oil and gas mixed therewith passes into the tube 19, said tube 19 in its descent, creates a partial vacuum at its upper end in the chamber 9^a, which draws in 110

a quantity of gas and fluid, equal in quantity to the partial vacuum thus created. The gas and oil thus drawn in between the tubes 19 and 29, will separate, and the gas will rise 5 into the chamber 9^a. When the up-stroke comes, the displacement in the chamber 9^a made by the tube 19, will force the fluid down from between 19 and 29 into 19, and in this manner the chamber 9^a will gradually be filled with gas. 10

The length of the tubes 19 and 29 is determined by having the tubes lap the length of the stroke, plus space enough, and a little more, to make up for the partial vacuum 15 caused by the tube 19 on down-stroke. In other words, the tubes must lap enough so that the fluid will not rise from the top of the tube 19 on down-stroke of the pump.

The important feature of improvement 20 consists of the tubes 19 and 29 which separate a quantity of gas from the fluid being pumped and hold the gas thus separated in such a manner that said gas acts as a packing between the cups or packing of 25 the plunger, thus keeping the sand from reaching these parts after it has passed with the fluid above the plunger. When it is necessary to pull the plunger to be repaired, the rods are drawn up until the 30 tube 19 comes against the collar 27 whereupon the member 22, with the attached parts, is drawn through the tubing and out of the well. When these parts are lowered back into place, the shoulder at the top of 35 the piston-rod will force the member 22 and its attached parts down into the tubular section 10 until the plunger 13 comes in contact with the standing-valve 6. The piston-rod 20 is as long as the member 22: 40 and tube 29, plus the length of the stroke of the pump. If the plunger should be drawn up too far, the member 22 will adjust itself in the tubular section 10 to the stroke of the pump. Another advantage of 45 this self-adjustment is that if sand should settle in the tube 19 when the pump is idle, and cause the tubes 19 and 29 to stick together, they could reciprocate together until the sand is finally forced out, whereupon 50 the member 22 would automatically adjust itself and become stationary in the tubular section 10.

What I claim is:

1. In oil well or like pumps, the combination 55 with a suitable casing, of a plunger working in said casing, an automatically operated valve controlling the supply of fluid to said casing, a valve controlling the passage of fluid to a point above said plunger, an upwardly extending tube connect- 60 ed to said plunger, a retaining member above said plunger, a tube connected to said retaining member, extending downwardly therefrom, a piston-rod connected to 65 said plunger, passing up through said

last named tube and retaining member, and a gas chamber intermediate said retaining member and said plunger.

2. In oil well or like pumps, the combination 70 with a suitable casing, of a plunger working in said casing, an automatically operated valve controlling the supply of fluid to said casing, a valve controlling the passage of fluid to a point above said plunger, an upwardly extending tube connected to 75 said plunger, a self retaining member above said plunger, a tube connected to said retaining member extending downwardly therefrom, a piston-rod connected to said plunger, and a gas-chamber intermediate 80 said retaining member and said plunger.

3. In oil well or like pumps, the combination 85 with a suitable casing, of a plunger working in said casing, an automatically operated valve controlling the supply of fluid to said casing, a valve controlling the passage of fluid to a point above said plunger, an upwardly extending tube connected to 90 said plunger, a retaining member above said plunger, a tube connected to said retaining member extending downwardly therefrom and telescoping with said upwardly extending tube, a piston-rod connected to said plunger, and an enlargement 95 on said casing, forming a gas chamber intermediate said retaining member and said plunger.

4. In oil well or like pumps, the combination 100 with a suitable casing, of a plunger working in said casing, an automatically operated valve controlling the supply of fluid to said casing, a valve controlling the passage of fluid to a point above said plunger, an upwardly extending tube connected to 105 said plunger, a retaining member above said plunger, a tube connected to said retaining member, extending downwardly therefrom and telescoping with said upwardly extending tube, a piston-rod connected to said chamber, whereby the fluid will not rise 110 from the top of said upwardly extending tube on the down-stroke of the pump, a piston-rod connected to said plunger, and a gas chamber intermediate said retaining member and said plunger. 115

5. In oil well or like pumps, the combination 120 with a suitable casing, of a plunger working in said casing, an automatically operated valve controlling the supply of fluid to said casing, the valve controlling the passage of fluid to a point above said plunger, an upwardly extending tube connected to 125 said plunger, a retaining member above said plunger, an expansion ring engaging said retaining member and said casing, a tube connected to said retaining member extending downwardly therefrom, a piston-rod connected to said plunger, and a gas chamber intermediate said retaining member and said plunger. 130

6. In oil well or like pumps, the combination with a suitable casing, of a plunger working in said casing, an automatically operated valve controlling the supply of fluid to said casing, the valve controlling the passage of fluid to a point above said plunger, an upwardly extending tube connected to said plunger, a retaining member above said plunger, packing interposed between 10 said retaining member and said casing, a tube connected to said retaining member

extending downwardly therefrom, a piston-rod connected to said plunger, and a gas chamber intermediate said retaining member and said plunger.

In testimony whereof, I, the said CHARLES W. BELL, have hereunto set my hand.

CHARLES W. BELL.
